UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET CUTTING AND FOLDING MACHINE.

1,193,449.

Specification of Letters Patent.

Patented Aug. 1, 1916.

Application filed June 4, 1915. Serial No. 32,170.

To all whom it may concern:

Be it known that I, HOWARD M. BARBER, a citizen of the United States, and resident of Stonington, in the county of New London and State of Connecticut, have invented 5 a new and useful Improvement in Sheet Cutting and Folding Machines, of which the following is a specification.

The object of this invention is to provide 10 means whereby the speed of continuously moving groups of sheets may be retarded and the groups of sheets folded off at a surface speed less than the speed of travel of the web as it passes through the press and 15 into the cutting and folding machine.

In sheet cutting and folding machines as heretofore produced where the folding mechanism operated at the speed of the press, the output of the press was materially 20 limited by the inability of the folding mechanism to act successfully at as high a speed as the press was capable of operating, the speed of the press being thereby necessarily tied down to the highest efficient speed of the 25 folding mechanism.

By my invention, a folding mechanism operating at a lesser speed than that of the press can be used in conjunction with the press without additional strain on the folding 30 mechanism thereby permitting the running of the press at a much higher rate of speed than heretofore possible.

A practical embodiment of my invention is represented in the accompanying drawings, in which—Figure 1 represents the machine in side elevation, Fig. 2 represents a 35 diagrammatic section taken from front to rear intermediate the side frames, and Fig. 3 represents a section taken from front to rear adjacent to the far side frame.

The near side frame of the machine is denoted by 1 and the far side frame by 2.

The web as it passes from the press, not shown herein, is led over the roller 3 and 45 from thence downwardly between the pair of coacting rotary cutters 4, 5, carried by suitable shafts 6, 7, mounted in bearings on the side frames 1, 2. In the present instance, this pair of coacting rotary cutters 50 4, 5, are shown as having three sets of coacting blades. The web passes through the cutters 4, 5, and the feed rollers 8, 9, to a rotary collecting cylinder 10 carried by a

shaft 11, which collecting cylinder is herein shown as having three sets of grippers 12, 55 13, 14.

The collecting cylinder 10 coacts with the first transfer cylinder 15 carried by the shaft 16, which cylinder is provided with one set of grippers 17. A sheet guide 18 extends 60 partway around the collecting cylinder 10 and a sheet guide 19 extends partway around the first transfer cylinder 15. The second transfer cylinder, denoted by 20, is carried by the shaft 21 and is provided with 65 a set of grippers 22, which grippers are arranged to coact with the set of grippers 17 of the first transfer cylinder to receive a group of sheets therefrom.

The male folding cylinder 23 is carried by 70 the shaft 24 and it is provided with two sets of grippers 25, 26, and two folding blades 27, 28. The grippers 25, 26, are arranged to successively coact with the grippers 22 of the second transfer cylinder 20 for receiving 75 the group of sheets therefrom.

A sheet guide 29 extends partway around the male folding cylinder 23. The female folding cylinder 30 is carried by the shaft 31 and it is provided with two sets of folding 80 jaws 32, 33, arranged to coact, respectively, with the folding blades 27, 28, of the male folding cylinder 23.

The delivery cylinder 34 is carried by the shaft 35 and is provided with a set of grippers 85 36 arranged to successively receive the folded groups of sheets from the folding jaws 32, 33, and deliver the sheets to any desired delivery device, such as the endless pocketed delivery carrier 37.

The folded groups of sheets may be slit lengthwise of their travel on the delivery cylinder 34 into two or more sections by one or more slitting disks 38 carried by the shaft 39.

The rotary cutters 4, 5, the collecting cylinder 10, and the first transfer cylinder 15, are driven at the speed of the web and the press through the train of gears 40, 41, 42, 43, 44, 45, 46, 47, 48. The folding cylinders 100 23, 30, and the delivery cylinder 34, are driven at substantially half the surface speed of the web through the train of gears 49, 50, 51. The endless pocketed delivery carrier 37 is driven at the desired relative 105 speed to bring its pockets into position to

receive the signatures from the delivery cylinder 34 by the train of gears designated by the numeral 52.

The second transfer cylinder 21 is driven 5 at a variable surface speed from the first transfer cylinder 15 through the irregular gears 53, 54, the relationship of these gears being such that the grippers 22 on the second transfer reel 20 will be traveling at 10 the surface speed of the first transfer cylinder 15 at the time the group of sheets are transferred from the grippers 17 of the first transfer cylinder and the surface speed of the grippers 22 will be reduced to the surface speed of the male folding cylinder 23 at 15 the time the sheets are transferred from the grippers 22 to the grippers 25 or 26.

In the arrangement of the parts herein shown, a collected group of four sheets is 20 transferred to the first transfer cylinder 15 every one and one third revolution of the collecting cylinder 10 and every revolution of the first transfer cylinder 15.

The speed of the grouping of sheets is reduced by the second transfer cylinder 20 so 25 that they are traveling at substantially one-half their original speed when transferred to the grippers 25 or 26 of the male folding cylinder 23.

30 It will thus be seen that two groups of sheets are transferred to the male folding cylinder 23 every revolution of the male folding cylinder. These groups of sheets are successively folded off to the female folding cylinder 30 and from thence transferred successively to the delivery cylinder 34 where they may be slit and delivered to the pocketed delivery carrier 37.

A movable cam 55 is arranged in position 40 to open the grippers of the collecting cylinder at the proper times to transfer the collected groups of sheets to the first transfer cylinder. Stationary cams 56, 57, are arranged in position to operate the grippers 17 of the first transfer cylinder 15 at the proper times to receive and transfer the groups of sheets. Stationary cams 58, 59, are arranged in position to operate the grippers 22 of the second transfer cylinder at the proper time 45 to receive and transfer the groups of sheets. Stationary grippers 60, 61, are provided for operating the grippers 25 and 26 at the proper times to receive and release the groups of sheets.

55 A box cam 62 is provided for floating the folding jaws 32, 33, to cause them to properly coat with their respective folding blades 27, 28. Stationary cams 63, 64, are provided for opening the folding jaws at 60 the proper time to receive the groups of sheets at the folding operation and for delivering the folded groups of sheets to the delivery cylinder 34.

A stationary cam 65 is provided in posi-

tion to open the grippers 36 of the delivery 65 cylinder at the proper times to deposit the successive groups of sheets into the pocketed delivery carrier and for receiving the groups of sheets from the female folding cylinder 30.

In operation: The web, as it comes from the press, passes down between the coacting rotary cutters 4, 5, through the feed rolls 8, 9, to the collecting cylinder 10. A collected group of four sheets is transferred 70 every one and one-third revolutions of the collecting cylinder 10 to the first transfer cylinder 15 every revolution thereof. The surface speed of the feeding rollers 8, 9, the collecting cylinder 10 and the first transfer 75 cylinder 15, are the same but are slightly in excess of the speed of the web, as to give a space between the leading and back edges of each group of sheets for permitting the operation of the grippers when transferring 80 the group of sheets from the collecting cylinder 10 to the first transfer cylinder 15.

Each group of sheets is transferred to the second transfer cylinder 20 at a speed slightly in excess of the speed of the web and 85 is slowed down by the second transfer cylinder, in the present instance to about one-half the speed of the web and the group of sheets at this retarded speed is transferred to the male folding cylinder 23, which cylinder 90 travels at about half the speed of the web and takes two groups of sheets at each revolution thereof. The groups of sheets are folded off to the female folding cylinder 30 and are transferred therefrom to the delivery cylinder 34 where the groups of sheets 95 may be slit lengthwise of their travel and deposited into the delivery carrier 37.

It will thus be seen that the folding mechanism can successfully operate upon sheets 105 cut from a web traveling at a much higher speed than heretofore thus materially increasing the output of the press.

By the term "cylinder" as used in the description, I contemplate any suitable means 110 for passing the sheets and signatures through the prescribed paths and by the term "grippers" I wish to include any engaging devices suitable for the purpose of leading the sheets or signatures through said 115 prescribed paths.

It is evident that various changes may be resorted to in the construction, form and arrangement of the various parts without departing from the spirit and scope of my invention; and hence I do not wish to limit myself strictly to the form herein shown and described, but

What I claim is:—

1. In a machine of the character described, 125 means for cutting sheets from a traveling web, sheet folding mechanism traveling at a lesser speed than the web and means for

gradually retarding the sheets and feeding them to the folding mechanism at the speed thereof.

2. In a machine of the character described, 5 means for cutting sheets from a traveling web, sheet folding mechanism traveling at about half the speed of the web and means for gradually retarding the sheets and feeding them to the folding mechanism at the 10 speed thereof.

3. In a machine of the character described, a sheet carrying mechanism traveling at a certain speed, a sheet folding mechanism traveling at a lesser speed and an interposed 15 variable speed transfer mechanism.

4. In a machine of the character described, a sheet carrying mechanism traveling at a certain speed, a sheet folding mechanism traveling at a lesser speed and a variable speed transfer mechanism arranged 20 to take the sheets at the speed of the carrying mechanism and transfer the sheets at the speed of the folding mechanism.

5. In a machine of the character described, 25 a sheet collecting mechanism traveling at a certain speed, a sheet folding mechanism traveling at a lesser speed and an interposed variable speed transfer mechanism.

6. In a machine of the character described, 30 a sheet collecting mechanism traveling at a certain speed, a sheet folding mechanism traveling at a lesser speed and a variable speed transfer mechanism arranged to take the sheets at the speed of the collecting mechanism and transfer the sheets at 35 the speed of the folding mechanism.

7. In a machine of the character described, 40 a sheet carrying mechanism traveling at a certain speed, a sheet folding mechanism traveling at a lesser speed and a sheet transfer mechanism arranged to gradually retard the sheets as they pass from the carrying mechanism to the folding mechanism.

8. In a machine of the character described, 45 a sheet collecting mechanism traveling at a certain speed, a sheet folding mechanism traveling at a lesser speed and a sheet transfer mechanism arranged to gradually retard the sheets as they pass from the collecting mechanism to the folding mechanism.

9. In a machine of the character described, 50 a sheet collecting cylinder traveling at a certain surface speed, a sheet folding cylinder traveling at a lesser surface speed and an interposed sheet transfer cylinder having a variable surface speed, operable to take the sheets at the speed of the collecting cylinder and to transfer the sheets at the 55 speed of the folding cylinder.

10. In a machine of the character de-

scribed, a sheet collecting cylinder traveling at a certain surface speed, a first sheet transfer cylinder traveling at the same surface speed, a sheet folding cylinder traveling at 65 a lesser surface speed and a second sheet transfer cylinder having a variable surface speed, operable to take the sheets from the first transfer cylinder at the speed of the collecting cylinder and to transfer the sheets 70 to the folding cylinder at the speed thereof.

11. In a machine of the character described, 75 means for cutting sheets from a traveling web, mechanism traveling at a little greater speed than the web for collecting sheets cut therefrom, sheet folding mechanism traveling at a lesser speed and sheet transfer mechanism arranged to gradually retard the sheets as they pass from the collecting mechanism to the folding mechanism.

12. In a machine of the character described, 80 means for cutting sheets from a traveling web, mechanism traveling at a little greater speed than the web for collecting sheets cut therefrom, sheet folding mechanism traveling at a lesser speed and a variable speed transfer mechanism arranged to take the sheets at the speed of the collecting mechanism and to transfer the sheets at 85 the speed of the folding mechanism.

13. In a machine of the character described, 90 means for cutting sheets from a traveling web, a sheet carrying cylinder traveling at a certain surface speed, sheet 95 folding cylinders having two pairs of co-acting folding-off devices traveling at about one-half the surface speed of the sheet carrying cylinder and a variable speed sheet transfer cylinder arranged to take the sheets 100 from the carrying cylinder at the speed thereof and transfer the sheets to one of the folding cylinders at the speed thereof.

14. In a machine of the character described, 105 means for cutting sheets from a traveling web, a sheet collecting cylinder traveling at a surface speed slightly in excess of that of the web, a first sheet transfer cylinder traveling at the surface speed of the collecting cylinder, sheet folding cylinders 110 traveling at about one-half the surface speed of the collecting and first transfer cylinders and a variable speed second sheet transfer cylinder arranged to take the sheets from the first transfer cylinder at the speed 115 thereof and to transfer the sheets to one of the folding cylinders at the speed thereof.

In testimony that I claim the foregoing as my invention I have signed my name this twenty-seventh day of May, A. D. 1915. 120

HOWARD M. BARBER.
